BEDSPRING

Harry B. Sklar, Los Angeles, Calif.

Application February 14, 1934, Serial No. 711,125

4 Claims. (Cl. 5—260)

My invention is a continuation in part as a division of my patent application Serial No. 675,896, filed June 15, 1933, for a Crimping machine for bed springs, or the like.

5. An object of my invention is to form a bed spring or the like with a border wire having a continuous groove and to secure the upper wire of coiled springs adjacent the border wire to such border wire by fitting the upper turn of the 10 coiled spring in the groove of the border wire and then crimping the border wire to close the outer portion of the wire around the wire of the spring, thus retaining the wire of the spring in the groove of the border wire.

15. One of the objects of my invention is to assemble the coiled springs and a border wire with a horizontal groove by inserting a portion of the upper loop of the coiled springs in the horizontal groove and then crimping the lips of the border 20 wire at the groove to firmly attach the springs and the border wire. This crimping may be effectively done by a machine such as disclosed in my patent application Serial No. 675,896 in which the crimping dies have a rectilinear motion in opposite directions and the portion engaging the lips of the border wire on opposite sides of the groove are beveled. Thus in the action of crimping, the lips of the border wire are subjected to a cold forging and upsetting operation.

25. This bends the lips inwardly toward each other and the displacement of the metal of the border wire forces the inserted part of the loop to have a snug fit against the base of the groove and thus toward the axial center of the border wire. The 30 procedure of upsetting and crimping the lips forms flattened surfaces on the outside of the border wire, these surfaces therefore forming planes, which planes are at an angle to a plane through the center of the border wire and the 35 axial center of the inserted portion of the loop.

Another object and feature of my invention is to form the border with a vertical groove which is preferably continuous and extends upwardly from the lower side of the border wire. In this 40 construction, the upper coil of the coiled spring has an upwardly bent section or hump which fits in the vertical groove of the border wire adjacent the groove then being crimped or bent over the upwardly bent section of the spring. This 45 crimping is preferably of such a manner as to firmly secure the border wire and the coiled spring, as with this construction, there is less danger of the crystallizing of the spring. The 50 upwardly bent section of the spring may be formed on an upward curve, or it may have an

offset section with substantially short vertical arms.

The hump in the loop of the coiled spring may be effectively made by the apparatus disclosed in my pending application, Serial No. 5,226, for 5 Automatic groove cutter and crimper for bed spring assembly; filed February 6, 1935. However, other types of machines or procedures may be used to form upwardly projecting humps in the upper loop of the springs, such humps either 10 having a gradual curve or substantially vertical ends with a connecting section between such ends. The crimping of the lips of the border wire on opposite sides of the vertical groove may 15 be done by crimping dies, such as disclosed in my patent application, Serial No. 675,896 above mentioned, the dies being positioned to operate, however, in a horizontal line instead of a vertical line, as shown in such patent application.

Another feature relates to forming the vertical 20 offset portion of the spring in a straight line, that is, occupying a vertical plane in order to properly fit in the straight portions of the continuous groove, but where the coiled spring engages a curved corner of the border wire, the vertical 25 offset portion of the spring must be made on a curve to conform to the curved corner of the border wire.

I prefer to crimp the lips on opposite sides of the vertical groove of the border wire by combined upsetting and cold forging operation such 30 as disclosed in my patent application Serial No. 675,896 above mentioned, in which the inward pressing of the lips of the border wire gives a displacement of the lips of the border and such 35 displacement engaging the hump of the loop forces the hump snugly into the base of the vertical groove toward the axial center of the border wire. The outside surface of the lips is 40 preferably flattened, each flattened surface forming a plane and these planes being at an angle to the vertical plane through the axis of the groove and the axis of the inserted portion of the hump of the loop.

My invention is illustrated in connection with 45 the accompanying drawings in which Fig. 1 is a plan taken in the direction of the arrow 1 of Fig. 2 of a portion of a bed spring, the lower angle iron being omitted.

Fig. 2 may be considered a vertical section on 50 the line 2—2 of Fig. 1 in the direction of the arrows, the coil springs being illustrated in elevation.

Fig. 3 is an enlarged perspective view of a section of the border wire. 55

Fig. 4 is a view similar to Fig. 3 with the hump on the coil inserted in the vertical groove of the border wire.

Fig. 5 is a view similar to Fig. 4 showing the border wire crimped to secure the coil spring and the border wire.

Fig. 6 is a partial perspective view of the upper turn of a coil spring showing a curved type of hump for inserting in the vertical groove of the border wire.

Fig. 7 is a view similar to Fig. 8 showing another type of offset hump on the coil spring.

Fig. 8 is a plan taken in the direction of the arrow 8 of Fig. 9 of another form of attaching the coil spring and border wire.

Fig. 9 is a vertical section on the line 9—9 of Fig. 8 in the direction of the arrows, the coil springs, however, being illustrated in elevation.

Fig. 10 is a perspective view of a section of the border wire showing the groove in a horizontal plane.

Fig. 11 is a view similar to Fig. 10 illustrating a portion of the upper turn of the coil spring fitted in a continuous longitudinal groove.

25. Fig. 12 is a view similar to Fig. 11 showing the border wire crimped and forming a hinged attachment of the border wire and the coil of the spring.

Referring first to the construction of Figs. 8 30 through 12, a section of a bed spring is indicated by the numeral 11, and the border wire by the numeral 12. A lower angle iron 13 holds the supporting bars 14 from which there are upwardly extending coil springs 15, which springs 35 are usually a combination of spiral and helical coils.

In my invention, the border wire has a longitudinal groove 16 extending the full length of the wire. This has an inner cylindrical section 40 17 sufficient to accommodate the curvature of the upper turn 18 of the springs located adjacent the border wire. The upper turn 18 is substantially circular, and only a small section of the arc extends into the groove 16. The groove is 45 illustrated as being in a horizontal plane. In assembling, the upper turn of the coil spring fits into the continuous groove as shown in Figs. 8 and 11, and portions of the border wire are crimped as indicated at 19 to attach the coil spring to the border wire. Crimping may be 50 done by the machine illustrated in my patent application Serial No. 675,896 above mentioned, or any other suitable type of crimping, or pressing the crimped ends 20 of sections of the border wire sufficiently close together to hold the upper 55 turn of the spring in the groove 16.

When in forming the construction of Figs. 8 through 12 I employ a crimping mechanism such as disclosed in my application Serial No. 675,896 60 above mentioned, as the crimping dies operate in opposite directions in a rectilinear motion and in alignment and, further, as each of these dies has a beveled end the lips on opposite sides of the groove of the border wire are subjected to an upsetting and cold forging operation. The 65 displacement of the lips towards each other causes the inserted portion of the loop to be pressed tightly against the base 17 in the groove 16, that is, toward the axial center of the border wire, so that the portion of the loop of the spring 70 occupies a central position, as indicated at 23 in Fig. 12. This type of crimping forms flattened surfaces on the border wire at each of the lips, these flattened surfaces being in planes which 75 form an angle relative one to the other and to

the plane through the axis of the border wire and the inserted section of the loop.

In the construction of Figs. 1 through 7, the general form of the spring is the same as above described. However, in this arrangement, the 5 border wire 30 has a continuous longitudinal groove 31 extending vertically upwardly from the lower side of the wire. This groove preferably has a rounded upper end 32 formed to the curvature of the wire 33 of the upper loop of a 10 coiled spring 34. In one form illustrated in Fig. 6, a hump 35 is made in this upper turn, this hump extending upwardly, and where it engages in the longitudinal groove, the wire on the hump portion and adjacent thereto is in a vertical plane 15 in order to fit in the groove. The border wire is then crimped as indicated at 36, the points or fingers of the crimp 37 may be pressed either close together or in close contact with the wire of the hump to attach the coil spring in a rigid 20 relation to the border wire.

In the construction of Fig. 7, the hump 38 is formed with vertical end pieces 39 and a connecting strip 40. These all being in a vertical plane to fit in a straight groove, the border wire being 25 crimped as shown in Fig. 5, with a tight crimp to form a rigid connection. It is manifest that both the constructions of Figs. 6 and 7 may be made on a curve to accommodate the curved corner formed by a border wire of the bed spring. The 30 crimp shown in Fig. 5 may be made by slightly modifying the machine in my above mentioned patent application Serial No. 675,896 above mentioned.

As above mentioned, the crimp, such as shown 35 in Fig. 5, may be made by a machine similar to that of my patent application No. 675,896, above mentioned. In this case, however, the reciprocating dies should operate in a horizontal line. The groove of the border wire may be in depth 40 substantially equal to the height the hump is upset above the plane of the upper loop of the spring. The action of crimping the lips of the border wire causes a type of upsetting action, the metal of the lips being displaced toward each other and 45 operating to force the upper point of a hump, such as 35 of Fig. 6 or the connecting strip 40 of Fig. 7, snugly against the upper rounded end 32 of the groove 31. In cases where the offset of the hump from the plane of the loop of the spring 50 is substantially equal to the depth of the groove in the border wire the hump is substantially disposed within the groove as shown in Fig. 5. The type of preferred crimp has flattened surfaces, these being at an angle to each other and meeting in a line substantially in a vertical plane 55 through the axis of the border wire and the section of the loop enclosed in the groove.

Various changes may be made in the details of construction without departing from the spirit 60 or scope of the invention as defined by the appended claims:

I claim:

1. In a bed spring construction, a rod formed with a downwardly opening groove, a spiral spring 65 formed with an offset portion in the top convolution thereof disposed substantially entirely within the groove and secured by crimping of the material of the rod adjacent the groove about the offset portion. 70

2. In a bed spring construction, a metal rod formed with a downwardly opening groove, a spring having a top convolution with an upwardly offset portion forming a hump, the hump having opposite end portions making an abrupt angle 75

with the remainder of the top convolution and a connecting portion substantially parallel to the base of the groove, the offset hump being substantially entirely disposed within the groove and secured by crimping of the material of the rod adjacent the groove inwardly, the end portions of the hump being at opposite ends of the crimp.

3. In a bed spring construction, a rod formed with a downwardly opening groove and a spiral spring formed with an offset portion in the top convolution thereof, secured within the groove wherein the offset portion is substantially equal in height to the depth of the groove, whereby

portions of the rod rest upon the top convolution of the spring adjacent the offset portion thereof.

4. In a bed spring construction, a rod formed with a downwardly opening groove and a spiral spring formed with an offset portion in the top convolution thereof, disposed within the groove and secured by crimping of the material of the rod adjacent the groove about the offset portion wherein the offset portion is substantially equal in height to the depth of the groove, whereby portions of the rod rest upon portions of the spring adjacent the offset portion.
